UNITED STATES PATENT OFFICE

JOSEPH GREENBERG, OF BROOKLYN, NEW YORK

MEDICATED HANKERCHIEF

Application filed September 19, 1929. Serial No. 393,619.

This invention relates to handkerchiefs, and has particular reference to the type that have associated therewith a medicament or odorous substance.

5 The invention is intended particularly for use by people having nose or throat afflictions, in which case the handkerchief would directly carry a suitable medication that could be applied as an inhalant in a neat, 10 convenient, and inconspicuous manner.

The invention may also be used to contain an odorous material as, for example, perfume or face powder.

One object of the invention is to provide 15 an improved handkerchief of the character described having a medication associated therewith restricted to one portion of the handkerchief and with another portion of the handkerchief substantially free of the 20 medication.

Handkerchiefs have been devised which have been treated with medication throughout their extent, but by this invention it is preferred to retain the major portion of the 25 handkerchief substantially free of medication to permit the handkerchief to be used in the usual manner for the reception of a catarrhal flow, or the like, without causing irritation to the nostrils.

30 Another object of the invention is to provide an improved handkerchief which is of a conventional nature as regards its appearance and which has a medication or odorous substance associated with any suitable edge portion thereof, as, for example, in the hem 35 of the handkerchief.

Another object is the provision of an improved device of the nature set forth by which the handkerchiefs may be packed and 40 stored without loss of the medication by evaporation.

A further object of the invention is to furnish an improved method and means for treating a handkerchief with medication or 45 odorous material.

Other objects and advantages of the invention will become apparent as the specification proceeds.

With the aforesaid objects in view, the 50 invention consists in the novel combinations

and arrangements of parts hereinafter described in their preferred embodiments, pointed out in the subjoined claims, and illustrated on the annexed drawing, wherein like parts are designated by the same reference characters throughout the several views.

In the drawing:

Figure 1 is a view of a handkerchief embodying the invention, the same having the edge thereof treated with a medication.

Fig. 2 is an enlarged sectional view taken on the line 2—2 of Fig. 1.

Fig. 3 is a view of a modification of the invention having medication applied within the hem of the handkerchief.

Fig. 4 is an enlarged sectional view taken on the line 4—4 of Fig. 3.

Fig. 5 is a fragmentary enlarged view showing a device for inserting a medication 70 into the tubular hem of a handkerchief, a part of the device being in section.

Fig. 6 is a view of a further modification of the invention with the medication in the form of large crystals in the hem thereof. 75

Fig. 7 is an enlarged view of a crystal of one particular type of medication.

Fig. 8 is a perspective view of a package sealing a medicated handkerchief in an air tight manner.

Fig. 9 is a view of a further modification of the invention having the medication applied in the manner of a suitably treated cord positioned within the hem of a handkerchief.

Fig. 10 is a view showing the medicated cord being applied to the handkerchief in course of manufacture.

Fig. 11 is a view showing a modification of the invention having capsules containing medication embodied in the hem of the handkerchief.

Fig. 12 is an enlarged sectional view of a capsule.

Fig. 13 is a view of a still further modification of the invention having a central medication receiving member.

The advantages of the invention as here outlined are best realized when all of its features and instrumentalities are combined in 100

one and the same structure, but, useful devices may be produced embodying less than the whole.

It will be obvious to those skilled in the art to which this invention appertains, that the same may be incorporated in several different constructions. The accompanying drawing, therefore, is submitted merely as showing the preferred exemplification of the invention.

Generally described, the invention provides a handkerchief having a medication or odorous substance associated with a predetermined small portion thereof, the remaining or substantially major portion of the handkerchief being substantially free of the medication so that the same may be used to receive a catarrhal flow or the like without irritation to the nostrils when the handkerchief is so used. Nevertheless the particular portion of the handkerchief that is treated as aforesaid may be applied to the nostrils when desired in order to act as an inhalent. It is preferred that the handkerchief be made of a fabric in the conventional shape and size so that the medication may be used in a convenient and inconspicuous manner and be carried in the pocket in the usual way. Within the scope of the invention, the same may be practised either by applying the medication to newly manufactured handkerchiefs or in course of manufacture thereof, or by applying the same to handkerchiefs after they are in the possession of the consumer. The medication may be used either along a substantial portion of the edge of a handkerchief or at the center thereof, though the former indicates the preferred arrangement. When the medication is used at the edge of a handkerchief, it may be applied at or within the tubular hem thereof, being inserted thereinto in any suitable manner as the hem is being formed or stitched, or after the hem has been completed by penetration of the wall of the hem. The medication may be applied in liquid, solid, or gaseous form according to any well known or convenient methods. In the solid form, the medication may be granulated and then inserted into the hem in any suitable manner. The hem thus constitutes for this purpose a medication holding pocket. When ground into a fine powder, the medication may be blown into the hem by a needle penetrating the wall thereof. It may also be inserted into the hem in the form of large crystals. Then again, it may be made up in a perforated capsule, and the latter sewn into the hem. The medication may also be applied to a cord or the like, and the latter sewn into the hem as the handkerchief is being manufactured. It is intended that the handkerchief shall be packed in an air tight manner so that it can be kept for any required time without evaporation of the medication. After the medication has evaporated, the

handkerchief may be washed and used thereafter in the usual manner without medication or additional medication may be applied as hereinafter indicated. It will be understood that the term "medication" is to be broadly construed as including substances of various kinds which are well known in the medical art, and even odorous materials such as perfume and powder can be applied within the scope of the invention.

Referring in detail to the drawing, 15 denotes a device embodying the invention. The same includes a conventional handkerchief made of fabric and having a hem 16 extending along the four edges thereof and stitched by any suitable line of stitching 17. A substantial length of the edge of the handkerchief is treated with medication by being inserted in a solution of the medicament. If desired an entire edge portion of the handkerchief on all four sides thereof may be thus treated as indicated by the dot dash line 18 which defines the portions of the handkerchief immersed into the liquid.

In Figs. 3 and 4 is shown a modification of the invention in which a conventional handkerchief 19 has a medication 20 inserted into the hem 21 along a substantial portion of the edge of the handkerchief, as, for example, along opposite sides thereof. The medication may be put into the hem as the same is being sewed, or it may be blown thereinto by any suitable device as, for example, that shown in Fig. 5. This comprises a hollow needle 22 having a beveled point 23 which is adapted to readily puncture the wall of the hem 21 of the handkerchief. Connected with the needle is a head 24 with which communicates a hose 25 that is connected to any suitable air supply. Extending from the head 24 is a vessel 26 that contains a granulated medication. The air from the hose 25 passes through a nozzle 27 and thus aspirates a quantity of the medication and blows the same through the needle 22 and into the tubular hem 21 of the handkerchief. Thus a substantial length of the hem of the handkerchief may be filled in a single operation. The hem may be perforated by the needles at as many points as may be necessary and after the needle has been withdrawn the fabric will contract and substantially close the opening.

In Fig. 6 is shown a modification of the handkerchief 28 having relatively large crystals of medication 29 within the hem 30 thereof. These crystals may be sewn into the hem coincident with the formation of the latter or they may be inserted by penetrating the walls of the hem. As the crystals of the medication assume an elongated pointed form, they can readily pierce the fabric of the hem and therefore be caused to readily enter the same. Any number of the crystals may be so disposed within the hem and in any

suitable spaced relation therealong. After they have evaporated, other crystals can be inserted into the hem and the crystals can be separately packed in air tight containers and 5 sold to the consumer for this purpose.

In Fig. 8 is shown a package 31 which encloses a handkerchief in an air-tight manner to prevent evaporation of the medicament, thereby permitting the handkerchief 10 to be stored away for any required length of time without losing its freshness. The package 31 may be of any particular type or construction and in a simple form of the device may be made of paper which is suitably folded and sealed with adhesive.

In Figs. 9 and 10 is shown a further modification of a handkerchief and a method of constructing the same. This handkerchief 32 has a medicated fibrous member or cord 33 20 disposed within the end 34 thereof along a substantial portion of the edge of the handkerchief, or all along the four sides thereof as may be necessary. The said cord is preferably applied as the handkerchief is being 25 manufactured since the hem 34 is readily folded thereover coincident with the stitching operation. The said cord may be supplied in any suitable or convenient manner as, for example, from a drum 35, and the 30 latter may be enclosed in a casing 36 to avoid evaporation of the medicament. A small opening 37 is provided in the casing through which the cord passes into the handkerchief.

In Fig. 11 is shown a further modification of a handkerchief 38, the same having a conventional hem 39 in which are contained 35 medicament containing bodies 40. The latter may be made up in any convenient manner. For example, an encasement in the 40 form of capsules, cachet, or poultice may be used. A capsule 41 is shown as being perforated at 43 and having a cap 43. Medication 44 may be inserted into the capsule in 45 the form of comparatively large crystals which will not pass through the perforations 42. Nevertheless the medication may slowly evaporate and act as an inhalent in the handkerchief. The capsule is of course intended 50 to be applied to the hem as the same is being stitched in the course of the manufacture of the handkerchief.

In all of the various forms of the handkerchief hereinbefore described, it is noted 55 that the medication is associated with the handkerchief along the edge portion thereof, leaving the major portion and particularly the entire center part of the handkerchief substantially free of medication except 60 as the same may slightly permeate thereinto. Thus the handkerchief may be used with the medication as an inhalent, while the central portion of the handkerchief is at all times available for the reception of a catarrhal 65 flow. The handkerchief is of conventional

and neat appearance, and it can be applied without making the user conspicuous.

In Fig. 13 is shown a still further modification of the invention in which a handkerchief 45 has a central medication receiving member or pocket 46 which may be stitched thereto at 46. The said member can be made of any suitable material, whether fabric, celluloid, or the like and it may be secured to the handkerchief by stitching or gluing along 70 the line 47. The pocket thus afforded contains the medication which may be inserted into the same with the formation of the pocket or by penetration of a wall thereof. When thus arranged only a relatively small 75 portion of the handkerchief contains the medication while the relatively large portion thereof surrounding the pocket is substantially free of the same for the conventional use of the handkerchief.

It will thus be seen that I have provided a device which fulfills the several objects of the invention and which is well adapted to meet the conditions of practical use.

I claim:

1. A device of the character described including a handkerchief having a hem and a separate carrier of an odorous medication in the hem, the main portion of the handkerchief being substantially free of medication.

2. A device of the character described including a handkerchief and a ribbon like odorous medication carrier extending solely along an edged portion thereof, the rest of the handkerchief being substantially free of 100 medication.

3. A device of the character described including a handkerchief having separate crystals of medication in the hem portion thereof at predetermined points in the hem, the remainder of the handkerchief being substantially free of medication.

4. A handkerchief made of fabric and having an integral stitched tubular element at a side portion thereof, and a separate deposit 110 of crystals of odorous medication within the tubular space in the said element, the remainder of the handkerchief being substantially free of medication.

In testimony whereof I affix my signature. 115
JOSEPH GREENBERG.
